UNITED STATES PATENT OFFICE.

GILBERT W. GOODRIDGE, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

FUSE.

Application filed May 18, 1921. Serial No. 470,500.

To all whom it may concern:

Be it known that I, GILBERT W. GOODRIDGE, a citizen of the United States of America, and residing in the city of Bridgeport, 5 county of Fairfield, and State of Connecticut, have invented certain new and useful Improvements in Fuses, of which the following is a specification.

My invention relates to fuses, and particularly to a fuse of the plug type with renewable fuse cartridge, the object of my invention being to provide a simple and rugged construction conveniently handled, readily manufactured, and efficient in operation.

In the accompanying drawings—

Fig. 1 is a vertical section through a fuse plug in which my invention is embodied in one form;

20 Figs. 2 to 6 combined constitute a dropped perspective of the fuse plug, the figures showing consecutively perspective views of the insulating body, the screw shell, the reinforcing washer, the rivet and insulating 25 cap;

Fig. 7 is a perspective of the renewable fuse cartridge showing one end cap detached;

Fig. 8 is a perspective of the fuse strip;

30 Figs. 9 and 10 are partial vertical sections showing spring-holding means of different types by which the fuse cartridge is maintained in position; and

Fig. 11 is a side elevation of a fuse cap showing another device for this purpose.

Referring to the drawings, which illustrate the invention in a form subject to various modifications, the plug element of the device comprises a pair of insulating 40 members 9 and 10, the former constituting the insulating body of the plug, and the latter the manipulating cap. The body 9 is arranged at the entering end of the plug and is provided with a central longitudinally. 45 extending chamber or passage 11 to receive the renewable fuse cartridge 12. An exterior shoulder 13 adjacent the nose of the body 9 affords an abutment engaged by the spun-over flange 14 of the screw shell side 50 contact 15. The latter has an end web 16 provided with radial ribs 17 and a centering boss 18 with aperture 19. The web 16 rests in a seat 20 formed in the inner face of the cap 10, and having channels 21 to receive

the ribs 17. The boss 18 enters a corresponding well 22 in the cap 10 and its hole 19 registers with hole 23 to receive the rivet 24. The latter is passed through the holes 19, the 23 and spun over in the recess 25 in the outer face of the button 10.

Preferably, a reinforcing washer 26 is interposed between the head of the rivet 24 and the web 16 of the screw shell, not only to reinforce and thus protect the web against injury during the riveting operation, but also to press the web ribs 17 in the channels 21. Upon the fastening of the parts together by the rivet 24, not only are the buttons 9 and 10 assembled, but the engagement between the ribs 17 and channels 21 firmly established, thus insuring the rotation of the screw shell with the cap 10 in both directions, that is to say, during the insertion and removal of the plug.

A center contact for the plug is afforded by one of the end caps 27 of the cartridge fuse 12, when the latter is inserted in the chamber 11 of the button 9. The other cap 28 of the fuse cartridge bears against the inner face of the washer 26 and thus establishes electrical connection through the washer 26 with the screw shell side contact 15. Between the caps 27 and 28 of the fuse cartridge extends the fuse strip 29, the ends 30 of which are angled over the ends of the cartridge 35 casing 12. When the plug is inserted in a receptacle, with the cap 27 of the cartridge firmly bottomed against the center contact of the receptacle, the draw-up pressure exerted through the screw shell 15 presses the caps 27 and 28 firmly against the ends of the fuse strip and insures good electrical connection between the latter and the caps. In order to support the ends of the fuse strip and prevent them from being forced into the insulating paper casing of the cartridge, I provide the ends of the latter with metal 40 ferrules 31, over which the ends 30 of the fuse 35 strip 29 are angled. These ferrules preferably take the form of U-shaped rings spun or otherwise compressed on the ends of the cartridge casing. Moreover, these metal 45 rings 31 are not subject to shrinkage or other variation in dimensions, to which the paper casing of the cartridge is possibly subject, and they thus insure good contact between the caps 27 and 28 and the bent-over ends 50 of the fuse strip. The cartridge element

may be filled with a gas-absorbing powder 32, in which the fuse element is embedded, thus minimizing danger of injury to the parts on the rupture of the fuse.

5 While the fuse cartridge may be freely mounted in position as shown in Fig. 1, I prefer to provide some means for holding it in the fuse chamber 11. Friction means of different types are indicated in Figs. 9, 10 and 11. Thus in Fig. 9 one of the end caps (28) has riveted thereto a spring fork 280 which projects into and frictionally grips the inner face of the hollow rivet 24. In Fig. 10 a spider with spring finger 281 is 15 riveted to the cap and engages the walls of the fuse chamber 11. While in Fig. 11 the cap has spring teats 282 formed in its side flange for the same purpose.

As an added feature of safety, I provide 20 the screw shell with a ring 33 of insulating material adjacent the cap button 10, which serves to protect the lineman against accidental contact with the shell during the manipulation of the plug.

25 The particular nature of the mechanical connection between the screw shell and the cap 10 to insure their rotation as a unit, may be variously modified. Similarly, the end ferrules 31 of the cartridge are not necessary under all conditions, but they are deemed advisable as a safety factor of the construction.

The caps 27 and 28 sleeve freely over the 30 end of the cartridge casing with no other engagement than the frictional grip of a close fit. On the blowing of the fuse element, it is possible to renew the fuse strip, but inasmuch as the cartridge fuse element is of very inexpensive construction, it is preferred to discard the blown cartridge and 35 substitute a fresh one, without attempting to substitute a fuse strip in the cartridge. The buttons 9 and 10 are simple to mold and present a rugged insulating body to which the metal parts are readily attached and all 40 assembled by the simple expedient of spinning over the end of the single rivet 24. The tubular construction of the latter enables the lineman to readily force out the fuse 45 cartridge, should it adhere, by inserting the end of a screw driver through the rivet into the fuse chamber, where it bears directly 50 on the end of the fuse cap.

Various modifications in details of construction will readily occur to those skilled 55 in the art, without departing from the underlying thought of my invention as embodied in the construction shown, or as pointed out in the following claims:

I claim—

1. A fuse device of the plug type having cap and body elements of insulating material, a screw shell side contact encasing the body element and having in assembled condition an end web engaged between the 60 adjacent faces of the cap and body elements, and an adjacent cylindrical non-threaded area, said body element having a longitudinally extending chamber open at the entering end of the plug to receive a renewable 65 fuse cartridge, together with an external insulating ring arranged on said cylindrical portion of the said screw shell adjacent and confined between the threaded area of the shell and the cap element to prevent 70 accidental contact with the shell during 75 the manipulation of the plug.

2. In a fuse device of the plug type described, a fuse cartridge having an insulating body, contact rings on the ends of said 80 body, a fuse having its ends angled over said contact rings, and end caps passed freely over said ends into frictional engagement therewith and with the bent-over ends of 85 the fuse strip.

3. A fuse device of the plug type having cap and body elements of insulating material, a screw shell side contact encasing the body element and having in assembled condition an end web engaged between the 90 adjacent faces of the cap and body elements, said body element having a longitudinally extending chamber open at the entering end of the plug to receive a renewable fuse cartridge, together with a reinforcing washer 95 interposed between the body member and shell web, and securing means passing through the cap, web and washer and serving to hold the parts assembled.

4. A fuse device of the plug type having cap and body elements of insulating material, a screw shell side contact encasing the body element and having in assembled condition an end web engaged between the 100 adjacent faces of the cap and body elements, said body element having a longitudinally extending chamber open at the entering end of the plug to receive a renewable fuse cartridge, together with a reinforcing washer 105 interposed between the body member and shell web, and a tubular rivet piercing said cap, web and washer and uniting the same, the hole in said rivet opening to the chamber in the body element.

In testimony whereof I have signed my 110 name to this specification.

GILBERT W. GOODRIDGE.
